THERMIONIC VALVE APPARATUS FOR USE
ON VERY SHORT WAVES

Norman Eustace Davis, Ernest Green, and Alfred Weedon Hall, Chelmsford, England, assignors to Radio Corporation of America, a corporation of Delaware

Application June 26, 1937, Serial No. 150,444
In Great Britain June 26, 1936

9 Claims. (Cl. 179—171)

This invention, which is for improvements in or modifications of the invention claimed in our copending application Serial No. 8,470, filed Feb. 27, 1935, relates to thermionic valve or vacuum tube apparatus suitable for use on very short waves and more specifically to thermionic valve arrangements suitable for use in radio transmitters for operation upon wave lengths of the order of ten meters, or less. An important application of the invention is to television transmitters.

According to the parent invention, thermionic valve apparatus adapted to operate on very short wave lengths comprises in combination, a pair of symmetrically connected thermionic valves of the fluid-cooled type, in which the anode forms part of the envelope each mounted in and having its anode electrically connected to a metal screen or housing, said housings having their adjacent walls parallel or approximately parallel and spaced from one another, a movable conductor structure located between said adjacent walls and adapted in conjunction with said walls to constitute an anode circuit tuning condenser, a movable metal member in electrostatic association with a further wall of each of said housings, said metal members each in conjunction with the associated housing wall constituting a neutralizing condenser included in a circuit extending between the anode of one valve and the grid of the other, and a symmetrical cooling pipe arrangement extending between the anode cooling jackets and constituting a symmetrical anode circuit inductance.

The present invention provides certain constructional detail improvements in or modifications of valve apparatus in accordance with the parent invention.

In the specific embodiment described and illustrated in our parent copending application, supra, there is a slidably mounted output circuit unit which is mechanically independent of the rest of the apparatus and comprises a symmetrically arranged inductance which is adapted to be coupled magnetically to the anode circuit of the valves, the degree of coupling being adjustable by sliding the unit. This output circuit unit comprises an inductance (11a) in Fig. 1 of our copending application Ser. No. 8,470, one end of which is connected to earth through a variable condenser (11c) and the other end of which is connected to an output feeder through a similar variable condenser (11b). A feature of the present invention is concerned with the provision of an improved output circuit unit for perform-

ing the functions of the unit 11b, 11a, 11c illustrated in the parent specification and according to the said feature of the present invention this unit comprises a pair of tubular condensers each consisting of two concentric tubes one inside the other and relatively movable axially, the movable tubes being arranged to be moved together for capacity adjustment and each carrying and being electrically connected to one end of the inductance, one of the fixed tubes being adjustably and conductively attached to an earthed carrier member (the unit as a whole being carried by this attachment) and the other fixed tube being adapted for connection to an output feeder.

The accompanying Figs. 1 to 5 show a preferred form of output circuit unit in accordance with this feature of the invention, Figs. 1, 2, 3, 4 and 5 being respectively a front elevation, a side elevation, a plan, an underside plan, and a section through the line AB of Fig. 1 with the coil omitted. Figs. 6 and 7 show a preferred construction of the blocking condenser that is a further feature of the invention, Fig. 6 is an elevation partly in section and Fig. 7 is a plan. Fig. 8 shows diagrammatically the position of the condenser of Figs. 6 and 7 in the circuit. Fig. 9 shows the arrangement of the cooling chambers for the valves and the neutralizing and anode circuit tuning condensers. In the construction of Figs. 1 through 5, the inductance (11a of Fig. 1 of application Ser. No. 8,470) is in the form of a two-turn rectangular "pancake" coil 111a composed of metal tubing through which cooling fluid may be passed if desired. The two condensers (11b, 11c of Fig. 1 of the parent specification) are constituted each by a pair of metal tubes 111b, 211b or 111c, 211c coaxially arranged one inside the other. The outer tubes 211b and 211c are parallel, side by side, and are fixed to an insulated body member 111 of plate-like form, the said outer tubes being fixed thereto by phosphorbronze bands 211, 311 which are drawn tight round the tubes to grip them. The inner tubes 111b and 111c are carried by being fitted into apertures in an insulating bridge piece 411 extending at right angles to the tube axes and fixed to a slideable insulating slide member 511 which extends in a direction parallel to the tube axes and can slide in the direction of its length in suitable guides on the face of the body member 111 opposite that on which the outer tubes are held. The coil 111a is mechanically fixed to the inner tubes each end of the coil 211a, 311a being attached to and carried from one end of one or other of the inner tubes 111b, 111c. Thus,

by moving the slide member 511 the capacities of both condensers will be similarly varied (for tuning purposes) the inner tubes being telescoped into or out of the outer tubes and the coil moving 5 with them. One of the outer tubes 211b is connected to a plate on which is a terminal 711 for an output feeder and the other tube is mechanically and electrically connected to a clamp member 811 which embraces an elongated cylindrical 10 metal carrier 911 from which the whole unit is carried and which is earthed. The carrier member is hollow and its axis is parallel to the tube axes. A handle or shaft 1011 for facilitating 15 adjustment of the position of the unit relative to the carrier is preferably arranged coaxially within the said carrier. Means (1111) are provided for locking the adjustments provided. In use, the unit (with its output feeder) is carefully 20 pre-tuned and then it is adjusted on the carrier for optimum coupling as regards the coil. The tubular condenser design described is of great 25 advantage in minimizing stray capacity effects and giving good high frequency current distribution, low inductive reactance in the condensers themselves, and high frequency capacity values approximately to static values.

In the specific embodiment described and illustrated in the parent specification application Ser. No. 8,470 there are two valves feeding into 30 a tuned circuit comprising an inductance (9a and b—see Fig. 1 of application Ser. No. 8,470) which is coupled to the inductance (11a) in the output circuit unit and which connects the anodes (1, 2) of the valves together, anode feed being supplied 35 to the anodes via the electrical center of the coil 9a and b. In the case of a powerful transmitter, e. g., a 20 kw. transmitter—the oscillatory anode circuit current may be very high—e. g., about 90 40 amperes—and in order that a true balance of power generation may be obtained as between the two valves, it is very desirable to provide means whereby the anode feed currents may be separately measured. Accordingly, in accordance 45 with a further feature of this invention, the inductance 9a and b is divided centrally into two similar inductances which are connected together by a preferably tubular blocking condenser so that feed currents may be applied to the two valves separately via the two opposite terminals 50 of the blocking condenser. The blocking condenser is preferably of the tubular type in order to obtain the good high frequency current distribution and large effective surface for high frequency currents offered by this type of condenser.

A preferred construction embodying this feature of the present invention is illustrated in the accompanying Figs. 6 and 7 in which Fig. 6 is an elevation, partly in section and Fig. 7 is a plan. Referring to these figures, each of the two "half inductances" which together constitute the inductance 9a and b is constituted by a length of 60 closely spaced, parallel, conductive fluid cooling pipes (not shown) which lead at one end to rubber hose water supply connections (not shown) and at the other to the water cooling chamber for one of the valves (not shown). The tubular blocking condenser which is to connect the two "half inductances" together comprises two similar cylindrical metal tubes MT₁, MT₂ having 65 their axes in the same straight line, said tubes being arranged end-to-end but spaced a little apart; a centrally positioned layer LM of mica or other insulation which encircles both tubes but 70 does not extend to the outermost ends; and a

split phosphor-bronze band or clamp MBC which embraces the insulation and is tightened up about it (e. g., by means of clamp bolts and nuts at MBC1) so as to hold the tubes and insulation firmly. This condenser is thus in effect two 5 capacities in series, i. e., the capacity between one tube and the band MBC and that between said band and the other tube. The outer end of each tube is fixed to or unitarily formed with an arcuate part-cylindrical metal member MM₁ or MM₂, 10 embracing about a quarter of a circle, the axes of the part cylinders being parallel to one another and at right angles to the axes of the tubes. Attached to one end of each part cylindrical member is a metal strap or band MMC₁ or 15 MMC₂, whose other end is attached to a screwed stem MMS₁ or MMS₂, which passes through a bolt hole in said member and is adapted to receive a knurled nut, as shown. In use, the pipes (not shown) constituting the "half inductances" 20 are placed against the part-cylindrical members MM₁, MM₂ at the outer ends of the tubes, the straps MMC₁, MMC₂ attached to those members are passed round the said pipes, the screwed stems MMS₁, MMS₂ are inserted in their appropriate bolt holes and the knurled nuts are then 25 screwed tight so that the said straps clamp the pipes firmly against the appropriate part-cylindrical members so as to provide firm mechanical and electrical connection for the blocking condenser. The overall length of the condenser is, of course, made approximately equal to the distance between the "half inductances." It will be 30 appreciated that this overall length can be adjusted by slackening the clamp MBC which holds the tubes and moving said tubes nearer together or further apart. Obviously, however, the said tubes must not be allowed to touch one another. The clamp can be drawn very tight to prevent the occurrence of air pockets between the condenser 35 electrodes which might adversely affect high frequency current distribution. The accompanying Fig. 8 shows diagrammatically the position of the condenser of Figs. 6 and 7 in the circuit, the said condenser being marked BC in Fig. 8. In the 40 said Fig. 8, WS are rubber hose water columns, the instruments DCA and DCV are direct current D. C. voltage measuring instruments, respectively, the terminals FT; HT+ and HT-; GB+ and GB-; and FV are, respectively, filament supply 45 terminals, high tension supply terminals; grid bias supply terminals; and filament voltmeter terminals; and the other references correspond with those used in Fig. 1 of the parent case.

Another feature of this invention is concerned 55 with the arrangement of the cooling chambers for the valves and the neutralizing and anode circuit tuning condensers 8x, Y5Y, (see Fig. 1) of the parent specification. According to a further feature of this invention, the anode cooling 60 chamber proper of each valve is in communication with a flat metal cooling liquid box, the two boxes being parallel and spaced apart and the valves being positioned outwardly thereof, the anode circuit tuning condenser including a movable box-like conductor structure which is longitudinally slidable between the parallel walls of the spaced boxes and each of the neutralizing condensers including an electrode adjacent one of said walls. A preferred embodiment of this 65 feature is shown in diagrammatic perspective in Fig. 9. Here, there are two flat metal cooling boxes with their flat sides parallel and spaced apart and one valve V1 is mounted vertically outside one box CB1, the other valve V2 being 70

mounted vertically outside the other box CB2. Short fluid flow metal pipes FMP support the valves from their respective boxes and put the opposite ends of the respective valve anode jacks into communication with the opposite ends of the appropriate cooling box. Between the two cooling boxes is a slidably mounted box-like conductor structure BXC which with said boxes constitutes the anode circuit tuning condenser, this structure generally resembling the corresponding structure (5) of the parent specification and performing the same electrical functions. The functions of the walls YY (so far as this condenser is concerned) of the arrangement illustrated in the parent specification are thus performed by the flat cooling box walls between which the movable conductor structure is positioned. These said walls are also utilized to perform the functions of the walls XX of the arrangement illustrated in the parent specification, for the neutralizing condensers are constituted each by one of the said walls (of a cooling box) in conjunction with an electrode adjustably positioned adjacent thereto, there being two such electrodes—one adjacent a wall of each cooling box—in the space between the two boxes. Only one such electrode—which is marked EX—appears in Fig. 9. The "anode inductance" pipes communicate with the flat cooling boxes, as shown.

In one embodiment described in the parent specification and suitable for use where a wide bandpass is required, a substantial resistance is imparted to the inductance 9a and 9b by spraying the copper tubes constituting the said inductance with soft malleable annealed iron or material of similar properties. As a result of this, the high frequency currents, which will pass by reason of skin effect mostly along the outsides of the conductors 9a, 9b will suffer considerable loss due to the high permeability of the iron surface while at the same time the advantages of copper piping for carrying the water are still obtained. In broad principal, this method of obtaining loss to secure a desired inductance/resistance ratio consists in utilizing the water passing down the tubes 9a, 9b to dissipate the required proportion of energy; that is to say, the high frequency loss is induced by reason of the external soft iron coating but the heat generated by that loss is quickly and efficiently dissipated by reason of heat conduction through the copper pipe to the water. Although this method of introducing loss may be employed in carrying out the present invention, it is at present preferred to introduce the loss in the grid circuit. In accordance with another feature (not illustrated) of this invention, therefore, a fluid cooled input inductance, corresponding to the inductance 20a of Fig. 1 of specification application Ser. No. 8,470 and adjustably coupled by a trombone slide arrangement with an inductance corresponding to the inductance 18 (of the same figure), is shunted by a resistance consisting of a series of cylindrical resistance units which are physically parallel to one another but electrically in series and are disposed along a circle the axis of each cylindrical unit lying on an imaginary cylinder and being parallel to the axis thereof. The resistance units are air cooled, air being passed up through the resistance units which are formed hollow. The said resistance units are mounted over insulating nozzles in a circular air admission conduit member so that air passes from said nozzles up through the resistance units, the other ends of said units communicating with a common draw-

off pipe in which a motor driven fan is situated the fan serving to draw air along the exteriors and interiors of the units.

What is claimed is:

1. An improved radio transmitter arrangement comprising an input circuit and an output circuit, said output circuit having a high potential and a ground terminal, means for coupling said output circuit with a pair of symmetrically arranged electron discharge tubes, said means comprising two concentric tube condensers each having a movable tube and a tube which is normally fixed when said transmitter is in operation, said movable tubes being arranged to move together for capacity adjustment, and each being electrically connected to one end of an inductance, one of said normally fixed tubes being adjustably and conductively connected to said ground terminal, the other normally fixed tube being connected to the high potential terminal of said output circuit.

2. An improved radio transmitter arrangement comprising an input circuit and an output circuit, said output circuit having a high potential and a ground terminal, means for coupling said output circuit with a pair of symmetrically arranged electron discharge tubes, said means comprising a slidably mounted condenser unit arranged independently of the apparatus in the input circuit, said condenser unit having a symmetrically arranged inductance secured thereto which is magnetically coupled to the anode circuit of said symmetrically arranged tubes, the degree of coupling between said anode and said output circuit being determined by sliding said condenser unit.

3. An improved radio transmitter arrangement comprising an input circuit and an output circuit, said output circuit having a high potential and a ground terminal, means for coupling said output circuit with a pair of symmetrically arranged electron discharge tubes, said means comprising two concentric tube condensers, each having a fixed and a movable tube, said movable tubes being arranged to move together for capacity adjustment, an inductance coil, one of said fixed tubes being mechanically and electrically connected to one end of said inductance coil, one of said fixed tubes being adjustably and conductively connected to said ground terminal, the other fixed tube being connected to the high potential terminal of said output circuit.

4. An improved radio transmitter arrangement comprising an input circuit and an output circuit, said output circuit having a high potential and a ground terminal, means for coupling said output circuit with a pair of symmetrically arranged electron discharge tubes, said means comprising two concentric tube condensers each having a fixed and a movable tube, an insulating bridge member secured to said fixed tube, said movable tubes being arranged to slide through said bridge member for capacity adjustment, and each being electrically connected to one end of an inductance, one of said fixed tubes being adjustably and conductively connected to said ground terminal, the other fixed tube being connected to the high potential terminal of said output circuit.

5. In an improved radio transmitter arrangement comprising input and output circuits, said output circuit having a high potential and a ground terminal, means for coupling said output circuit with a pair of symmetrically arranged electron discharge tubes, said means comprising

an inductance and two concentric tube condensers each having a fixed and a movable tube, each end of said inductance connected to said movable tube condensers, a second inductance coupled to said first mentioned inductance and symmetrically divided into two portions, the outer ends of said inductance portions connected to the anode circuit of said electron discharge tubes, each of the two portions of said second inductance coupled together by a metallic member insulated from said portions and by a plurality of tubes forming a blocking condenser so that feed currents may be supplied to the two symmetrically arranged discharge tubes separately by means of two opposite terminals on said blocking condenser.

6. An improved radio transmitter arrangement comprising an input circuit and an output circuit, said output circuit having a high potential and a ground terminal, means for coupling said output circuit with a pair of symmetrically arranged electron discharge tubes, said means comprising an inductance and two concentric tube condensers each having a fixed and a movable tube, said inductance having each of its ends connected to said movable tubes, one of said fixed tubes being adjustably and inductively connected to said ground terminal, the other fixed tube being connected to the high potential terminal of said output circuit, a second inductance coil symmetrically divided at its center and connected together by a condenser comprising two fixed and two movable tubes each having their axis in the same straight line and arranged end-to-end but spaced apart from each other, a centrally positioned layer of insulation encircling both the said tubes, and a split band clamp embracing said layer of insulation and having means for tightening up so as to hold the tubes and insulation firmly in position, said movable tubes being connected to the divided center ends of said second inductance coil.

7. An improved radio transmitter arrangement comprising an input circuit and an output circuit, said output circuit having a high potential and a ground terminal, means for coupling said output circuit with a pair of symmetrically arranged electron discharge tubes, said means

comprising two concentric tube condensers each having a fixed and a movable tube, said movable tubes being arranged to move together for capacity adjustment, a pipe-like inductance coil secured to at least one of said concentric tubes, 5 one of said fixed tubes being adjustably and conductively connected to said ground terminal, the other fixed tube being connected to the high potential terminal of said output circuit.

8. An improved radio transmitter arrangement 10 comprising an input circuit and an output circuit, said output circuit having a high potential and a ground terminal, means for coupling said output circuit with a pair of symmetrically arranged electron discharge tubes, an anode cooling chamber for said electron discharge tubes, a flat metal cooling liquid box in fluid communication with each of the anodes of said tubes, the two boxes being arranged parallel to and spaced apart from each other, said electron discharge 15 devices being positioned outwardly thereof, two variable tuning condensers including a movable box-like conductor structure which is longitudinally slidable between the parallel walls of said cooling liquid boxes, a neutralizing condenser 20 having at least one of its electrodes adjacent one of said walls of said cooling liquid boxes.

9. An improved radio transmitter arrangement comprising an input circuit and an output circuit, said output circuit having a high potential 30 and a ground terminal, means for coupling said output circuit with a pair of symmetrically arranged electron discharge tubes, said means comprising two concentric tube condensers each having a fixed and a movable tube, said movable 35 tubes being arranged to move together for capacity adjustment, and each being electrically connected to one end of an inductance, a resistance in shunt with said inductance which serves to introduce losses to provide a desired width of 40 bandpass, one of said fixed tubes being adjustably and conductively connected to said ground terminal, the other fixed tube being connected to the high potential terminal of said output circuit.
